UNITED STATES PATENT OFFICE.

NELSON A. S. MILLER, OF WARREN, MINNESOTA.

FOLDING STEPLADDER.

1,315,979.

Specification of Letters Patent. Patented Sept. 16, 1919.

Application filed March 14, 1918. Serial No. 222,444.

To all whom it may concern:

Be it known that I, NELSON A. S. MILLER, a citizen of the United States, residing at Warren, in the county of Marshall and State 5 of Minnesota, have invented certain new and useful Improvements in Folding Step-ladders, of which the following is a specification.

- This invention relates to an improvement 10 in step-ladders, and more particularly to a folding structure in which the steps and side rails as well as the leg or prop are adapted to be folded or collapsed to make the ladder structure more compact for the storage.
- 15 An object of my invention is to provide a ladder of the character set forth which has the steps connected with the side rails in hinged mounting so that in the folding of the ladder the steps and the side rails will 20 be brought substantially into contact with one another, the steps being so mounted with respect to the side rails that they will be substantially in horizontal planes when the ladder is set up for use.
- 25 A further object resides in embodying brace members with the side rails and so mounting the same that when the ladder is set up for use the steps and the side rails will be positively braced and secured against 30 collapsing and against side twisting or wabbling.

Yet another object lies in providing a prop or leg which will conform substantially to the compact lines of the ladder 35 when the same is brought to the folded position and which has connection with and to brace both side rails of the ladder when the structure is set up for use.

With the above and other objects in view, 40 which will appear in the specification, drawings, and claims, my invention consists in certain novel features of construction and combinations of parts which will be herein-after more fully set forth.

45 In the drawings:—

Figure 1 is a view in front elevation of a ladder constructed after the manner of my invention and with the parts set up for use;

Fig. 2 is a view in side elevation showing 50 the parts in the folded relation;

Fig. 3 is a front view of the structure shown in Fig. 2;

Fig. 4 is a view in side elevation showing the ladder set up as in Fig. 1;

Fig. 5 is a fragmentary view at the upper 55 end of the ladder structure showing the manner of connecting the prop or leg;

Fig. 6 is a fragmentary view showing a slightly modified form of top step; and

Fig. 7 is a detail sectional view on the line 60 7-7 of Fig. 6.

Fig. 8 is a detail view, partly in section, showing the connection of the braces to the ladder stiles.

The side rails 1 and 2 of the ladder proper 65 have the hinge eyes 3 and 4 mounted in conjunction therewith at points spaced to correspond with the spacing of the steps of the ladder construction to be made up, and the steps 5 have fittings 6 and 7 on the ends 70 thereof which embrace the bars 8 adapted to be received through the eyes 3 and 4 so that the steps are hingedly connected with the side rails. As the ladder will invariably be used with the step section inclining 75 over from the vertical, and as the steps are desired to be in substantially horizontal planes when the ladder is in use, it is preferable that the eyes 3 and 4 of the side rails 1 and 2 be disposed somewhat off from lines 80 taken directly transversely across the side rails 1 and 2, and as the side rails 1 and 2 are moved to fold the steps down and to bring these side rails into proximity, the one side rail will be off-set from the other somewhat after the manner shown in Fig. 2, the degree of off-set of course depending upon the degree of departure from a right angular lining up of the eyes across the side rails. While I have set forth that eyes 3 and 4 are 90 carried by the side rails 1 and 2 and that the fittings 6 and 7 are mounted in conjunction with the steps 5, it will be appreciated that the arrangement of the parts might be reversed, and that in some instances hinges 95 of other types would be employed.

The ladder structure as above set forth can be folded to present a very compact form, or can be set up to present the steps 5 to be disposed transversely across between 100 the side rails 1 and 2 and substantially right angularly with respect thereto. However, in this set up relation the ladder structure has no stability. Braces 9 and 10 are con-

2
nected by means of pins or other suitable fastenings 11, upon the side rails 1 and 2 of the ladder preferably adjacent the upper ends thereof, and the remaining ends of the 5 brace members are provided with openings for reception of the pins 12 and 13 which are removably carried by the side rails adjacent the remaining extremities thereof. By pivotally mounting the brace members 9 and 10 10 and providing the same with openings to receive the pins 12 and 13, the brace members can be brought to a crossed relation on the rear side of the ladder structure and then when fitted to the pins 12 and 13 will 15 accomplish bracing of the ladder structure, which will make the same substantially rigid and will positively preclude swinging movement of the steps with respect to the side rails, or the reverse.

20 The ladder structure having braces mounted in conjunction therewith might be used after the manner of an ordinary ladder; however, it is desirable that a prop or leg, generally indicated at 14, be provided to 25 hold the ladder in the proper upright position for use without the necessity of leaning the same against a wall or other support. As the side rails 1 and 2, the steps 5, and the brace members 9 and 10, are so associated 30 that they can be set up in the position for use and can be folded to make the structure comparatively compact, it is of course understood that the prop or leg structure at 14 must allow this folding of the main structure and must itself be of such construction 35 that it will take up a minimum space. As is shown in Fig. 1, the prop or leg embraces the side members 15 and 16 which are connected together at their lower ends as shown 40 at 17, and these side members 15 and 16 are of wooden strips or are made up of such other resilient material that they can be spread at their ends to meet the side rails 1 and 2 of the ladder structure adjacent the 45 upper end thereof. A bearing eye 18 is carried by the side rail 2 adjacent the upper end thereof and is preferably so mounted that slight turning movement is permitted, and at substantially the same relative position the side rail 1 has an eye 19 mounted 50 fixedly thereon. A pin 20 connects the side member 16 of the leg or prop with the bearing eye 18, and a pin 21 is carried by the side member 15 to be fitted through the 55 opening of the eye 19 on the side rail 1 of the ladder, it of course being understood that the pin 21 is disposed on the inner side of the member 15 so that as fitted through the eye 19, the natural resiliency of the side 60 members 15 and 16 will preclude spreading of the side members sufficiently that the pin 21 would be displaced. As has been stated, the side members 15 and 16 are of resilient material and after the member 15 has been 65 sprung out to displace the pin 21 from the

eye 19, these two members 15 and 16 will come together so that when the remaining parts of the ladder are brought to the folded or collapsed relation the prop or leg portion 14 will be equally compact.

70 Under some circumstances it may be found desirable to provide a wider and longer top step for the ladder structure, which top step will serve as a shelf, and where this is desired the cross supporting 75 member 22 will be mounted between the side rails 1 and 2 substantially after the same manner as the top step of the embodiment illustrated in Fig. 1, and then supporting legs 23 and 24 are disposed to extend upwardly from this cross supporting member 22, the shelf or step 25 being mounted on the supporting legs. In this form of the structure, the lengthening out or broadening of the part 25 will not interfere with the 80 folding of the ladder and will not offer any material extension of the compact lines of the folded structure.

85 From the foregoing it will be seen that I have provided a step-ladder which is so constructed that not only are the steps and side rails foldably connected together, but also the bracing structure and the prop or leg for the support of the ladder in the position for use, are likewise so constructed 90 and arranged that they can be connected in a manner to serve to brace and make the ladder structure rigid, or can be detached and folded to conform substantially to the 95 lines of the folded ladder structure proper.

100 While I have herein shown and described only certain specific forms and mountings of the various parts, it will be understood that other types of hinge connections might be employed between the steps and side rails, 105 that the braces and the prop might be connected in other manners than here shown, and that a number of changes and variations might be resorted to, in view of which fact I wish to be limited to only such points 110 as may be set forth in the claims.

I claim:—

115 1. A folding step-ladder including side rails having steps foldably connected therewith, means to brace said parts to hold the ladder structure in a set-up position for use, a prop member including a pair of side members connected together, means by which the free end of one of the side members is connected adjacent the upper end 120 of one of the side rails of the ladder structure to be capable of swinging movement, and means by which the free end of the remaining side member is detachably connected with the remaining side rail.

125 2. A step-ladder comprising a plurality of side rails, step portions secured thereto and capable of being folded to permit one side rail to be moved flat upon the other side rail, an upper step portion pivotally secured 130

near the upper edge of said side rails, supporting legs carried by said upper step portion near the respective ends thereof, a shelf carried by the upper ends of said supporting legs and spaced from the upper step portion for permitting the easy swinging of said upper step portion upon said side rails and allowing the free movement of one side

rail toward the other while the ladder is being folded.

In testimony whereof I affix my signature in presence of two witnesses.

NELSON A. S. MILLER.
